UNITED STATES PATENT OFFICE

WILLIAM D. KENNEDY, OF WESTERN SPRINGS, ILLINOIS

BAG CONSTRUCTION

Application filed January 23, 1930. Serial No. 422,744.

This invention relates to bags of the type wherein a drawstring is provided around the mouth for closing same and has reference more particularly to the arranging of the drawstring in the edge of a length of material so that the latter may be cut into sections or blanks for making the bags and each section or blank will have extra length of drawstring projecting therefrom to afford external ends which may be readily grasped for drawing the mouth of the bag closed.

The principal objects of my invention are, to provide an improved method of making bags of the type above referred to; to assemble the draw string in lengths of bag material which are subsequently cut into blanks from which the bags are made; to arrange the draw string in the edge of the bag material so that each bag blank cut therefrom has extra length of draw string for external projecting ends; to insure a protruding of the ends of the draw string from each blank and thus facilitate further construction of the bag; to anchor the draw string of the bags so as to prevent accidental pulling out thereof without such anchoring interfering with the intended function and operation of the draw string; to accomplish the anchoring as the draw string is being assembled in the bag material; and in general to simplify, improve and facilitate the construction of bags of the type above referred to.

On the drawing:

Fig. 1 is a perspective view of a bag made in accordance with my invention;

Fig. 2 is a plan view of a length of bag fabric from which the bag blanks are cut, and shows the manner of assembling the draw string in the edge thereof; and

Fig. 3 is an enlarged fragmentary view, partly in section, of an edge portion of a bag blank showing the arrangement of the draw string in the edge thereof and the method of anchoring the draw string to prevent pulling out.

Referring to the drawing in which I have for the purpose of illustration shown my invention in connection with a mailing bag having an address tag at the closed end, although it is to be understood that the invention is

not limited to this particular type of bag, Fig. 1 shows the completed bag which consists of a piece of fabric which is folded along the edge 1 forming the two sides 2 and 3 which are stitched together along the edges 4 and 5, the bag being turned inside out after the stitching so that the seams come on the inside of the bag. In the present form of bag an address tag 6 is attached along the lower edge 5, being inserted and stitched between the edges 5 of the bag are being stitched together.

A hem is formed around the mouth of the bag by turning in the edge portion 7 and stitching at 8 so as to provide a tubular pocket 9 around the mouth in which is located a draw string 10 having ends projecting at the edge 4 of the bag which may be readily grasped for drawing and tying the mouth of the bag closed.

The ends of the draw string 10 are usually left loose so that they may be readily tied together to hold the mouth of the bag closed when the bag is used, and consequently, unless the drawstring is fastened to the bag it is likely to be accidentally pulled out of the tubular pocket 9 thus occasioning considerable loss of time in replacing the string or expense of discarding the bags. To avoid this objectionable feature I anchor my draw string preferably at or near the folded edge 1 so that it cannot be pulled out of the tubular pocket 9, and at the same time does not interfere with the use of the bag and draw string, this anchoring being effected according to my present invention in the operation of forming the hem and installing the draw string in the edge of the bag material. This is conveniently accomplished by providing a loop 11 in the draw string at or near the place where the fold 1 occurs in the finished bag and fastening said loop 11 under the folded edge 7 by the stitching 8 which forms the draw string hem.

To make this bag according to my present invention, I take a length of bag material of a width suitable for the length of the bags to be made therefrom and form the draw string hem along the edge as shown at the top of Fig. 2 by folding over the edge 7 and

stitching along the line 8. The draw string is placed in the pocket 9 as the latter is formed, being arranged in the zig-zag or crimped form as shown at 12 so as to provide 5 the extra length required as hereafter indicated and as the draw string in the crimped form is fed in place the edge 7 is turned there-over and stitched.

The width of the crimped draw string is of 10 course less than the width of the pocket 9 so that the draw string is not caught in the stitching 8 and can in the later construction of the bag be pulled out straight. However, at suitable intervals a longer loop 11 is formed 15 in the crimped draw string, this being located according to the subsequent cutting of the length of material so as to come at or near the fold line 1 of the blanks, and these longer loops 11 are caught by the stitching 8, as 20 shown particularly in Fig. 3, so as to anchor the draw string at these points.

After the length of material is formed with the hem and crimped draw string 12 therein, it is cut into pieces or blanks of suitable size to make up into individual bags, 25 the lines of cutting being between the places where the longer loops 11 occur; for example, the length of material shown in Fig. 2 is cut along the lines A—A into separate pieces. 30 These pieces are then folded along the line B—B, at or near which the anchored loops 11 occur, and stitched along the bottom and side edges to form bags similar to that of Fig. 1.

The cutting of the length of material into 35 bag blanks, of course, cuts the crimped draw string 12 into lengths which on account of the crimping are sufficiently long to pull out at the edges of the blank and provide the projecting ends 10 which are required in the finished bag. It is to be noted, however, that 40 these cut blanks each has the draw string anchored at or near the fold 1 so that it can not be accidentally pulled out in the further construction or use of the bag.

45 Furthermore, when the bag blanks are cut from the continuous piece of bag material, it is not sufficient that the hem contain extra length of draw string. The ends must be readily available without fishing for them, so 50 that the draw string may be pulled out to its full length or engaged by mechanism in the further operations of completing the bag. With the draw string arranged in the crimped manner as herein described, this important 55 result occurs, as the severed ends of the draw string at the severed edges of the fabric, by reason of their crimped form, have a spring-like action and the ends snap or spring out of the ends of the pocket of the hem as indicated at 13 in Fig. 3, thus permitting the ends 60 to be grasped by hand or mechanical device for pulling out the draw string to its full length.

65 With this construction of and method of making up bag material, the making of the

bags may be continuous and automatic as long pieces of bag material can be fed to mechanisms which crimp and lay the draw string in place and fold and stitch the hem there-over, and after this is done the length 70 of material may be cut into blanks and readily made up into the finished bags, particularly as the springing out of the ends of the draw string from the blanks insures that the draw string ends are available for engagement and 75 manipulation by mechanisms for pulling out and holding same in the further operations of completing the bag.

While I have shown and described my invention in a preferred form, I am aware that 80 various changes and modifications may be made without departing from the principles of my invention, the scope of which is to be determined by the appended claims.

I claim as my invention:

1. A blank for making a bag with a draw string around the mouth, said blank consisting of a piece of fabric having a pocket along one edge and a draw string puckered in the pocket to occupy a length thereof substantially less than the length of the draw string and providing extra length substantially in excess of the length of the pocket. 90

2. A fabric strip for making bags with a draw string around the mouth of each bag, 95 said strip being of a length to be divided into a plurality of bag blanks and said strip having a hem along the edge with a crimped draw string therein of a length substantially greater than the length of the hem. 100

3. A strip of bag making fabric having a fold along the edge and a cord of a length substantially greater than the length of the fold and formed with a plurality of successively looped portions within the fold to provide extra length for projecting ends. 105

4. A strip of bag making fabric having a lateral fold, and a cord formed with a plurality of successively looped portions within said fold, said loops extending transversely 110 of said fold.

5. In an article of manufacture, a fabric strip having a lateral fold, a cord looped transversely in said fold and running the entire length thereof, and means for anchoring said cord at intervals within said fold. 115

6. In an article of manufacture, a fabric strip having an inwardly turned lateral edge, stitching extending through said edge and the body of the fabric to form a lateral pocket, and a looped cord extending longitudinally through said pocket, certain of said loops being secured by said stitching. 120

7. A method for forming a bag fabric 125 which consists in puckering a cord longitudinally to form a plurality of successive loop portions adjacent the lateral edge of a flat strip of fabric material, turning said edge back over the looped cord, and securing said 130

edge to the body of the fabric by stitching to confine the looped cord therein.

8. A method for forming a bag fabric which consists in looping a cord adjacent to the lateral edge of a flat strip of fabric material, turning said edge back over the looped cord, and securing said edge to the body of the fabric by stitching, said stitching passing through certain of said loops.
- 10 9. A method for making a bag which consists in looping a cord adjacent the lateral edge of a flat strip of fabric material, turning said edge back over the looped cord, securing said edge to the body of the fabric
- 15 by stitching, cutting bag blanks from the strip thus formed, stitching together the ends of the blanks so cut, and stitching together the associated edges opposite the edge containing the cord.
- 20 10. The step in the method of making bags which consists in arranging longitudinally contracted a length of draw string material in a pocket along the edge of a strip of bag material so that the ends of the draw string material spring out of the pocket when the latter is cut into separate lengths.
